LIGATOR

Wilber Hart, Midwest, Wyo.

Application October 11, 1937, Serial No. 168,478

3 Claims. (Cl. 128—326)

My invention relates to surgical instruments and more particularly to improvements in so-called ligators for use in tying off blood vessels.

The primary object of the invention is the provision of an instrument of this character for placing a ligature and tying the same in deep narrow cavities in which it is difficult to place or manipulate a ligature with the fingers without tearing the wound.

10 The invention also comprehends other objects of a more or less subordinate nature all of which together with the exact nature of my improvements will become apparent when the following description and claims are read with reference to 15 the drawings accompanying and forming part of this specification.

In said drawings:—

Figure 1 is a view in front elevation of a ligator embodying my invention.

20 Figure 2 is a view in side elevation.

Figure 3 is a fragmentary view in front elevation drawn to an enlarged scale of the loop-holding end of the ligator.

25 Figure 4 is a view in transverse section taken on the line 4—4 of Figure 1 looking in the direction indicated by the arrows.

Figure 5 is a view in front elevation of the shank.

30 Figure 6 is a view in end elevation of the loop-holding end of the ligator.

Figure 7 is a view in end elevation of the tensioning slide, and

Figure 8 is a fragmentary view looking at the inner side of one end of the loop holder.

35 Referring to the drawings by numerals, in the illustrated embodiment thereof my improved ligator comprises a rod-like shank or stem 1 of steel, having a hand-grip end 2 to which a thumb-grip in the form of the usual metal ring 3 is attached by means of a socket 4 on said ring fitting over said end of the shank, and a thumb-screw 5 threaded through said socket and end. From the ring 3 to a point substantially midway of its ends the shank 1 is flattened, as at 6, to form a 40 key portion on said shank 1 terminating at said point in a stop shoulder 7. Preferably from the shoulder 7 the shank is reduced in size, as at 8, to the opposite end thereof to lighten the weight and thereby facilitate manipulation of the instrument. Slidably mounted on the portion 6 of the shank 1 is a tensioning slide, or carriage, 9 of 45 suitable metal comprising a guide sleeve 10 fitting on said portion 6 and pair of manipulating ears 11, extending from opposite sides of the sleeve 10, respectively, and apertured, as at 12, for the in-

sertion of the fingers of the operator therein. A pair of resilient clips 13 extend forwardly from the front of the sleeve 10 on opposite sides of the longitudinal center of the shank 1 for clamping a ligature to said sleeve in a manner to be described. 5

Extending from the end of the shank 1, opposite the hand-grip end 2, and disposed in the plane of said shank, is a bifurcated loop holder 14, of general horseshoe shape and bar-like structure, provided with a stud 15 threaded into said end of 10 the shank 1 and by means of which said holder is detachably secured to said shank with its free ends outwardly extending. Suitably secured to the free ends of the holder 14 are opposed pairs of clamping members 16 extending inwardly from 15 said ends adjacent the extremities thereof. The clamping members 16 are preferably formed of a semi-circular length of resilient wire attached at their ends to the holder 14, the members of each pair being arranged side-by-side for cooperating 20 clamping action. The holder 14 is provided with a pair of guide openings 17 therein in the bend thereof and upon opposite sides of the shank 1 respectively.

Referring to the use of the described ligator, the 25 ligature 18 is anchored at one end to the slide 9 by means of one of the described clips 13, it being understood that the slide 9 is positioned against the shoulder 7. The ligature 18 is then trained alongside the shank 1 and threaded through the 30 holder 14 by way of the guide openings 17 on the same side of the shank as said clip 13. From said openings 17 the ligature 18 is led across the holder 14 outwardly and clamped between the pair of clamping members 16 on the opposite 35 side of said holder and then looped across the free ends of the holder 14 and clamped between the other pair of clamping members 16. From the last mentioned clamping members 16 the ligature is wrapped loosely, at least twice, around 40 that portion thereof extending from the first mentioned aperture and then threaded through the other aperture 17 and led alongside the shank 1 to the carriage 9 to which the free end of the ligature is clamped by the other clip 13. 45 As will be clear from an inspection of Figure 3 the described disposition of the ligature 18 forms a loop in the holder 14 loosely tied and held in place by the clamping members 16 and openings 17 and arranged to be tied by tension exerted 50 on the ends of the ligature. With the ligature 18 thus arranged, the instrument is manipulated to locate or place the loop of the ligature over the vessel, or other bleeding point, and the slide 9 is moved by the fingers to exert a tension on the 55

ends of the ligature sufficient to pull the loop tight around said vessel. The ligator may then be freed from the ligature in any suitable manner as by cutting the latter.

5 The ligator described in the foregoing is especially useful in ligating vessels in performing tonsillectomies and in deep abdominal and kidney incisions. By its use insertion of the fingers and hand into the incision, and particularly into the 10 throat, is entirely obviated. Moreover by virtue of the described ligator, the ligature and point to be ligated can always be kept constantly in view thereby aiding in the careful handling of the tissues while ligating and thus reducing trauma.

15 It is thought that the foregoing will suffice to impart a clear understanding of the invention without further explanation.

Manifestly the invention as described is susceptible of modification without departing from 20 the inventive concept and right is herein reserved to all such modifications falling within the scope of the subjoined claims.

What I claim is:—

1. A ligator for use with a ligature having a 25 loop formed therein intermediate the ends thereof and comprising a rod-like shank provided at one end thereof with a thumb-accommodating ring, a slide splined on said shank for movement toward and from said ring and provided with 30 finger-grip apertures therein, a bifurcated holder mounted on the other end of said shank with the ends thereof outwardly extending, opposed pairs of resilient clamping members on the ends of said holder, respectively, for clampingly engaging the 35 loop of said ligature upon opposite sides thereof, and means on said slide for releasably securing the ends of the ligature thereto whereby tension may be exerted on said ligature ends by movement of said slide toward said ring.

40 2. A ligator for use with a ligature having a loop formed therein intermediate the ends thereof

and comprising a rod-like shank provided at one end thereof with a thumb-accommodating ring, a slide splined on said shank for movement toward and from said ring and provided with finger-grip apertures therein, a bifurcated holder mounted 5 on the other end of said shank with the ends thereof outwardly extending, opposed pairs of resilient clamping members on the ends of said holder, respectively, for clampingly engaging the 10 loop of said ligature upon opposite sides thereof, and means on said slide for releasably securing the ends of the ligature thereto whereby tension may be exerted on said ligature ends by movement of said slide toward said ring, said means comprising a pair of resilient clips, and the holder 15 having a pair of guide apertures in the bend thereof for the passage of the ends of the ligature therethrough.

3. A ligator for use with a ligature having a loop formed therein intermediate the ends thereof 20 and comprising a rod-like shank provided at one end thereof with a thumb-accommodating ring, a slide splined on the shank for movement toward and from said ring and provided with finger-grip apertures therein, a bifurcated holder 25 mounted on the other end of the shank with the ends thereof outwardly extending, means on the ends of said holder for detachably and slidably securing the opposite sides of the loop to said ends, respectively, whereby said loop is adjustably 30 suspended in said holder in opened condition, and means on the slide for releasably securing the ends of the ligature thereto whereby tension may be exerted on said ligature end by movement of the slide toward the ring, said means 35 comprising a pair of resilient clips, and the holder having a pair of guide apertures in the bend thereof for the passage of the ends of the ligature therethrough.

WILBER HART. 40
